WALL MOUNTED COSMETIC MIRROR

Shirley Tager, 3932 Stevely Ave., Los Angeles, Calif.

Filed Oct. 23, 1961, Ser. No. 67,230

Term of patent 14 years

(Cl. D86—10)

The broken lines in FIGURES 1 and 4 of the drawings indicating a wall mirror and a wall are for illustrative purposes only.

I claim:

The ornamental design for a wall mounted cosmetic mirror, as shown and described.
